HARRISON R. YOUNG, OF CATASAUQUA, PENNSYLVANIA.

REMOVABLE CALK FOR HORSESHOES.

1,069,311.

Specification of Letters Patent.

Patented Aug. 5, 1913.

Application filed April 1, 1913. Serial No. 758,099.

To all whom it may concern:

Be it known that I, HARRISON R. YOUNG, a citizen of the United States of America, and a resident of Catasauqua, county of 5 Lehigh, and State of Pennsylvania, have invented certain new and useful Improvements in Removable Calks for Horseshoes, of which the following is a specification, reference being had to the accompanying drawing, forming a part thereof.

My invention relates to horse-shoes and the like and one of its objects is to provide a rigidly affixed, removable calk for shoes of this character, that shall be simple and 15 durable in construction and easy to attach and detach.

Other objects will be set forth hereinafter.

I will describe my invention in the following specification and point out the novel 20 features thereof in appended claims.

Referring to the drawings: Figure 1 is a face or bottom plan view of a shoe constructed for and equipped with removable calks which are constructed and arranged in accordance with my invention. Fig. 2 is a sectional elevation on the line 2—2 of Fig. 1. Fig. 3 is another sectional elevation on the line 3—3 of Fig. 1. Fig. 4 is a perspective view on a larger scale, of one of the heel 25 sections of the shoe shown in Fig. 1, the heel calk being spaced from the section of the shoe to disclose in detail the structure of the coöperating parts.

Like characters of reference designate corresponding parts in all the figures.

10 is a horse-shoe formed in the usual manner with nail holes 11. The body of the shoe is preferably provided with a toe projection 7 and heel projections 8—8 which 40 increase the thickness of and thus reinforce the shoe at the points where calks are usually located.

Notches or slots 12—12 are provided on opposite edges of the shoe where it is reinforced by the projection 7, and notches or slots 13—13 and 14—14 are provided in the shoe at the reinforced heel portions. These notches produce spaced parallel shoulders 12^a, 13^a, 14^a and interposed rectangular sections 15—16 and 17 which are thicker and narrower in cross-section than the remainder of the shoe. A toe calk 18 is removably mounted on the section 15 and heel calks 19 and 20 are removably mounted on the sections 16 and 17. The toe calk 18 is longer than the heel calks 19 and 20, but is similar

to them in form, and each of the calks comprises a block which may be flat or sharpened as desired and is provided with a longitudinal rectangular mortise 22. As shown 60 in Fig. 4 of the drawings, the mortise is of such a size and its side walls 24—24 are of such a width that the calk fits onto the rectangular section 17 of the shoe between the shoulders. Bolts or machine screws 25 extend through holes 23 in the walls 24 and through corresponding holes in the shoe sections. Thus it appears that the calks are not only mortised to fit onto the rectangular sections of the shoe, but the shoe is provided with side notches forming parallel 65 shoulders between which the side projections of the calks extend. This arrangement makes the joint between each calk and the shoe a particular rigid one. There are however, no beveled or inclined surfaces such as are found on dove-tail joints and are liable to become damaged and to prevent the ready removal of the calk. With the arrangement 70 illustrated, the flat top surfaces of the projections are engaged by the flat under surfaces of the calks and consequently the weight of the animal does not tend to displace the calks but is advantageously sustained. Furthermore, there is no stress on 75 the bolts so they are not liable to be sheared off or damaged, but they hold the calks securely in place so that they cannot be displaced while in use, and the shoe, together 80 with the removable calks, can be easily 85 forged.

Two interchangeable sets of calks may be provided for each shoe if desired, one set having flat bearing surfaces and the other being sharpened or beveled to prevent slipping.

The body of the calk may be longer than the rectangular section of the shoe to which it is secured as is the toe calk 18 illustrated in the drawings, or the calk may be of the 95 same length as the corresponding shoe section as are the heel calks illustrated.

My invention is of course not limited to removable calks for shoes for horses, as distinguished from those adapted for use on 100 mules, oxen, etc., and I have used the term "horse-shoe" broadly as indicating a shoe of this general character.

What I claim is:

1. A horse-shoe having a projection extending from its face and opposite edge notches in the shoe extending at right angles

to the face, through said projection, arranged to form parallel spaced shoulders, separated by a rectangular shoe section of reduced width and increased thickness, and 5 a calk removably secured to said section and having projections fitted into said notches between the shoulders.

2. A horse-shoe having reinforcing projections extending from its face and open 10 ended opposite edge notches in the shoe extending at right angles to the face of the shoe and arranged to form spaced shoulders in the reinforced portions, separated by a rectangular shoe section of reduced width 15 and increased thickness, and toe and heel calks removably secured to said sections, each of said calks being mortised to fit onto the corresponding rectangular section of the shoe and arranged to fit between said shoulders.

20 3. A horse-shoe having reinforcing projections extending from its face with plane flat outer surfaces and open ended opposite

edge notches in the shoe extending at right angles to the face through the reinforcing projections and arranged to form parallel 25 spaced shoulders, separated by a rectangular section of reduced width and increased thickness, and toe and heel calks removably secured to said sections and having flat under surfaces to engage the flat outer surfaces of the reinforcing projections and sustain the weight of the animal, each of said calks being mortised to fit onto the corresponding rectangular section of the shoe and arranged to fit between said parallel spaced 30 shoulders.

In testimony whereof, I have hereunto set my hand, this 29th day of March, 1913, in the presence of two subscribing witnesses.

HARRISON R. YOUNG.
